UNITED STATES PATENT OFFICE.

DENNIS RYAN, OF SALT LAKE CITY, UTAH.

RAIL-FASTENING.

1,276,576.

Specification of Letters Patent. Patented Aug. 20, 1918.

Application filed June 10, 1918. Serial No. 289,191.

To all whom it may concern:

Be it known that I, DENNIS RYAN, a citizen of the United States, residing at Salt Lake City, in the county of Salt Lake and 5 State of Utah, have invented certain new and useful Improvements in Rail-Fastenings, of which the following is a specification.

This invention relates to improvements in 10 rail fastening devices, and it is the principal object of the invention to provide a rail fastening device which will serve to positively prevent creeping, spreading or other undue movement of rails engaged thereby and 15 which can be easily and quickly attached to the rails without the use of spikes or similar fastening devices.

Another and equally important object of 20 the invention is to provide the device with a novel form of joint whereby to receive and effectually secure the abutting rail ends against undue movement.

Other objects will be in part obvious and in part pointed out hereinafter.

25 The improvements in the details and arrangement of parts will be apparent from an inspection of the accompanying drawings, in connection with the specific description hereinafter contained, and wherein the 30 preferred embodiment of the invention is disclosed for the purpose of imparting a full understanding of the same.

In the drawings:

Figure 1 is a fragmentary top plan of a 35 railway track wherein the rails thereof are secured by my improved fastening devices,

Fig. 2 is a vertical transverse section taken on the line 2—2 of Fig. 1,

Fig. 3 is a similar section taken on a line 40 3—3 of Fig. 1, and

Fig. 4 is a fragmentary detail in perspective of a portion of the rail base showing the manner in which the same is formed when engaged by the improved fastening 45 devices.

Having more particular reference to the drawings, in connection with which like reference characters will designate corresponding parts throughout the several views, ' 50 designates the several rails of the track, which rails receive thereunder the base plates 1 and 2 of the fastening devices, said plates having rail base engaging arms 3 formed integral therewith, while portions of 55 the same are formed with slots to permit the connection of clamping arms 4 therewith,

which arms, as will be understood, are apertured and receive bolts 5 therethrough having nuts turned into engagement with their screw threaded extremities. Apertured extensions 6 and 7 are formed integral with the inner sides of the base plates 1 and 2, and, as will be noted, are arranged at substantially right angles thereto to permit engagement of the same and the fastening of 60 locking bolts 8 therethrough. Obviously, by forming the extensions 6 and 7 with a series of apertures, the same can be adjusted to tracks varying in width and positively connected by passing the bolts 8 through the 65 alined openings in said extensions 6 and 7.

In Fig. 2 I have shown a second form of the fastening device, this particular embodiment being designed for effecting a positive joint between the abutting ends of the rails, 70 such as indicated in Fig. 1, and to prevent longitudinal or transverse movement of the rails so secured. The fastening device in this particular form comprises base plates 9 and 10, the plate 10 being of greater width

80 than the plate 9 and serving to receive the abutting ends of the rails 'r thereon. A rail base engaging arm 11 is formed on one portion of the base plate 9 while a similar arm 12 is formed on the base plate 10 and, obviously, is of greater width than the arm 11. Clamping arms 13 and 14 are provided, the clamping arm 13 having a laterally extending apertured portion 15 which is adapted 85 to receive a connecting bolt 16 therethrough, 90 said bolt passing through an alined opening formed in the adjacent portion of the base plate 9. In this connection it is to be noted that the lateral portions of the clamping arms 4 and 13 are arranged in recessed 95 portions or seats formed in their respective base plates and, consequently, shifting of the same will be positively prevented when they are once engaged by their respective locking or connecting bolts. The clamping 100 arm 14 is provided with a series of slots in the upper portion thereof which are alined with other slots formed in the web portions of the abutting rails and in the clamping arm 12, which slots receive connecting bolts 105 17 therethrough for an obvious purpose. It is to be understood, that by forming slots in the clamping arms 12 and 14, movement of the abutting rail ends will be permitted upon expansion or contraction thereof. However, 110 such movement will not serve, in any way, to loosen the connection between the rails

and the fastening device engaged therewith. An apertured extension 18 is formed on the inner side of the base plate 10 and is received within the bifurcated end 19 of an 5 arm 20 which arm is provided with a series of openings adapted to be alined with similar openings formed in an extension 21 extending from the inner portion of the base plate 9 and arranged at substantially right angles 10 thereto. Bolts 22 are passed through the alined openings in the extensions and serve to effect a secure connection therebetween, which connection, if desired, can be adjusted to permit the adaption of the fastening device 15 vice to tracks varying in width. A pivot bolt 23 is passed through alined openings formed in the bifurcated end 19 and in the extension 18, thus, serving to pivotally connect the extension 20 to said base plate 10, thus, facilitating the engagement of the fastening device with the rails.

To positively prevent undue movement of the lower end of the clamping arm 14, elongated notches 24 may be and preferably are 25 formed in the adjacent portions of the bases of the rails *r* and are adapted to be alined with slots 24' formed in said clamping arm whereby to permit the passage of spikes or suitable fastening devices therethrough into 30 engagement with the tie or other bed receiving the fastening device.

From the foregoing it will be readily understood by persons skilled in the art that I have provided an exceedingly efficient and 35 simple form of fastening devices for rails whereby all undue movement of the rails with relation to each other will be positively prevented but which will allow the rails to adjust themselves upon expansion and 40 traction. Furthermore, the fastening devices, by reason of their construction, can be used in connection with tracks varying in

width, thus, rendering the same especially desirable in connection with temporary rail-way engineering operations.

45

I, of course, desire to have it understood that I do not confine the invention to the particular embodiments chosen for illustration herein, nor to the exact construction, arrangement, and adaption of parts shown 50 and described, but I reserve the right to make any changes and alterations that clearly fall within the spirit and scope of the invention.

55

I claim:

1. A rail fastening device including rail receiving means, a rigid apertured extension on the inner portion of one of said rail receiving means, a second apertured extension hinged for horizontal movement to the inner 60 portion of the remaining rail receiving means, and means for adjustably connecting said extensions.

2. A rail fastening device including base plates, rail base engaging arms on said plates, a rigid apertured extension carried on the inner portion of one of said base plates, a second apertured extension hinged to the inner portion of the remaining base plate, and means for adjustably connecting 70 said extensions.

3. A rail fastening device including base plates, rail base engaging arms formed integral with said plates, portions of said base plates being recessed to form seats, rail base 75 clamping arms engaged in said seats, an extension rigidly carried on the inner portion of one of said base plates, a second extension pivotally connected to the inner portion of the remaining base plate, and means for adjustably connecting said extensions.

In testimony whereof, I affix my signature hereto.

DENNIS RYAN.
